UNITED STATES PATENT OFFICE.

JOHN McCCLURE, OF GLENSIDE, PENNSYLVANIA.

INKING MECHANISM FOR PRINTING-PRESSES.

1,296,098.

Specification of Letters Patent.

Patented Mar. 4, 1919.

Application filed March 15, 1913. Serial No. 754,539.

To all whom it may concern:

Be it known that I, JOHN McCCLURE, a citizen of the United States of America, residing in Glenside, in the county of Montgomery and State of Pennsylvania, have invented certain new and useful Improvements in Inking Mechanism for Printing-Presses, of which the following is a true and exact description, reference being had 10 to the accompanying drawings, which form a part thereof.

My present invention relates to apparatus for supplying ink to printing presses, and particularly to inking apparatus of the kind 15 in which the ink is contained in an ink receptacle or reservoir, adapted to be removably inserted in feeding apparatus which is attached to the printing press, and comprises means for expelling ink from the receptacle 20 at the desired rate.

My improved inking apparatus is primarily devised for and is especially adapted for use with job printing presses which are operated intermittently, or at least not operated continuously with one kind of printing ink. With my improved inking apparatus when a printing operation requiring the use of ink contained in one receptacle is finished, the receptacle may be readily removed, and when the next printing operation is to take place, the same receptacle or a similar receptacle containing the same or a different kind of ink may then be inserted in the apparatus. Each receptacle may thus 30 be intermittently used until all the ink initially inserted therein is used up. This type of inking apparatus comprises the general advantages of keeping the ink, fully or partially filling the receptacle, clean and of protecting it for long periods from exposure to the atmosphere tending to dry out and oxidize the ink. Furthermore, it is inherently adapted to keep the ink wastage down to a practical minimum.

The general object of my invention is to provide apparatus of the character referred to which shall be simple in construction, relatively inexpensive to manufacture, and reliable in operation. More specific objects 45 of my invention are to provide apparatus which can be readily applied to existing printing presses of various types, which can be cleaned with a minimum expenditure of time and labor, which permits the rate at which the ink is fed to be adjusted quickly and readily, and which comprises simple and

effective means for preventing injury to the apparatus in case all the ink is expelled from the ink receptacle in use while the printing press is in operation. A further object of 60 my invention is to provide a simple and inexpensive type of ink receptacle for use in and as a part of the ink feeding apparatus proper.

The various features of novelty which 65 characterize my invention are pointed out with particularity in the claims annexed to and forming a part of this specification. For a better understanding of the invention, however, and of the advantages 70 possessed by it, reference should be had to the accompanying drawings and descriptive matter in which I have illustrated and described various forms in which my invention may be embodied.

Of the drawings:

Figure 1 is a somewhat diagrammatic elevation of a job printing press of well known, type having applied thereto a preferred form of my inking apparatus;

Fig. 2 is a view of the inking apparatus proper taken similarly to Fig. 1, but on a larger scale;

Fig. 3 is a view taken at right angles to the plane of Fig. 2, looking in the direction 85 of the arrow applied to Fig. 2;

Fig. 4 is a partial sectional elevation on the line 4—4 of Fig. 3;

Fig. 5 is an elevation of a yielding element employed and serving as a safety device under certain conditions, the element being shown in its collapsed condition;

Fig. 6 is a perspective view of one form of ink container;

Fig. 7 is a partial longitudinal section of 95 the receptacle shown in Fig. 6;

Fig. 8 is a view taken similarly to Fig. 7, showing a modified form of ink receptacle;

Fig. 9 is an elevation, partly broken away and in section, of another type of ink receptacle and holder therefor;

Fig. 10 is a transverse section of a modified form of holder, and ink receptacle therein;

Fig. 11 is a perspective view of a portion 105 of a modified form of feeding mechanism;

Fig. 12 is an elevation of a portion of the feeding shaft employed in Fig. 11; and

Fig. 13 is a partial end elevation of still another form of feeding mechanism.

The well known form of printing press illustrated somewhat diagrammatically and

conventionally in Figs. 1 and 2, comprises a stationary frame A, carrying a vertical platen A', and having pivotally connected to it at B' a swinging presser head B carrying a form B². The presser head B is oscillated on its fulcrum pivots B' by means of links C connecting the fulcrum pivots B³ to crank pins C' carried by crank disks C² which are mounted on a shaft connected by 5 gearing (not shown) to the main driving shaft C³ of the press. An oscillating frame D pivoted on the trunnion pivots B³ is caused to turn on the latter as the presser head B swings back and forth, by the link 10 connections D² between the frame D and the pivot pins A² carried by the frame A. At its upper ends the frame D carries the usual form rolls D' by which the printing ink is 15 transferred from the inking bed of the press to the form B². The inking bed is in the form of the usual rotary inking disk E.

The apparatus for supplying ink to the disk E comprises a roll J which I may call a fountain roll, mechanism for rotating this 20 roll, mechanism for expelling ink at the desired rate from an ink receptacle S against the roll J, a transfer or feeding roll M, and mechanism for moving the transfer roll back and forth between one position in which it 25 contacts with, is rotated by, and receives ink from the fountain roll J, and another position in which it contacts with and applies ink to the ink disk E.

As shown in the drawings the inking apparatus proper comprises a frame G secured 30 at one end to an arm F, which is suitably affixed at its other end to the presser head B of the press. As shown, the frame G is secured to the bracket arm F in the desired 35 adjustment with respect to the ink disk E by means of a central stud or bolt F' and a set of leveling screws F². The main power shaft H of the inking mechanism proper is journaled in the frame G. This shaft is 40 given an oscillatory movement by suitable connections to some moving part of the press proper. As shown in the drawings, the shaft H is connected to the oscillating frame D by means of an arm H' secured to one end 45 of the shaft H, a clamp H² detachably secured to a portion of the frame D, and a connecting rod H² pivotally connected at one end to the clamp H³ and at the other end to the arm H'. The shaft H carries at its other 50 end a gear sector I, which meshes with a spur gear J² secured to a shaft J' also journaled in the frame G. The shaft J' carries the fountain roll J, which is detachably secured to the shaft as by means of the set 55 screw J³. The roll J is preferably formed of metal and is advantageously so mounted as to have freedom for a limited amount of axial movement and if desired some suitable or usual form of end play device may be 60 employed to give it a limited amount of 65

axial movement as it is rotated first in one and then in the opposite direction. Each oscillation of the frame D preceding each impression made by the printing press imparts a corresponding oscillatory movement 70 to the shaft H and the sector I. The oscillatory movement imparted to the sector I is sufficient to give several turns to the fountain roll J, first in one direction and then in the reverse direction. As the sector I, moving from the position shown in Fig. 2, approaches the position shown in Fig. 1, a lug or projection I' carried by the sector I engages a pin or projection K² carried by an arm K', and thus imparts an oscillatory 75 movement to the latter and to the shaft K to which the arm K' is attached. At its free end the arm K' is formed with an open ended slot K⁴ receiving a pin L' secured to the U frame L, and adapted to slide in the 80 guideways formed by the lugs G' of the frame G. The transfer roll M, which may be a composition roll, is journaled in the forward ends of the frame L. The movement imparted to the frame L by the oscillation 85 of the arm K' is sufficient to move the roll M from its normal position, shown in full lines in Fig. 2, in which it is in contact with and rotated by the fountain roll J, into its second position in which it contacts with the 90 inking bed or disk E, as shown in dotted lines in Fig. 2. Springs L² operate to return the frame L to the position in which the roll M contacts with the fountain roll J when the return movement of the sector I permits. 95

The shaft K serves as means for transmitting motion to the ink expelling mechanism. For this purpose an arm K⁵ is secured to one end of the shaft K. A sleeve N slidably mounted on the arm K⁵ and adjustably clamped to the latter as by means of the thumb nut N carries a crank pin N². The latter is connected to and oscillates a pawl lever P by a connecting rod. Normally this connecting rod serves as a rigid connection 105 between the crank pin N² and the pawl lever P, but the connecting rod is adapted to serve as a safety device which will yield or collapse on a predetermined increase in the resistance to the oscillatory movement of the 110 pawl lever P. For this purpose the connecting rod is formed in two main sections O and O'. The section O is pivoted at its lower end on the crank pin N², and is formed at its bifurcated upper end with cam slots 115 O² receiving a stud O³ secured to the lower end of the upper main section O' which extends between the bifurcations of the section O. The section O' is pivoted at its upper end to the pawl lever P. The upper end 120 O⁴ of one bifurcation of the lower section extends at right angles to the length of the section and normally abuts against an arm O⁵ pivoted at O⁶ to the section O'. The arm O⁵ is normally held in the position shown 125 130

in Fig. 2 in which it bears against the flat end O^4 of the section O by a spring O^7 . When the resistance to the feeding movement of the pawl lever P exceeds a predetermined movement, the spring O^7 yields and the two sections O and O' of the connecting rod start to move relatively to one another in a direction parallel to their lengths. The inclined direction of the slots O^2 , however, cams the meeting ends of the two sections laterally apart and after a slight initial telescopic movement, the connecting rod breaks or collapses into the position shown in Fig. 5. On the return movement of the apparatus, the connecting rod O straightens out again and snaps into its original condition, and this yielding and subsequent straightening out of the connecting rod continues on each up and down stroke of the arm K^5 until the resistance to the oscillatory movement of the pawl lever P is reduced to the normal amount. A strap G^{10} is adapted to arrest the backward motion of the pawl lever P and insure the straightening out of the connecting rod O , O' on each downward swing of the arm K^5 .

The pawl lever P is mounted to oscillate about the axis of a shaft Q . The latter carries a ratchet wheel Q' which is engaged and given a partial turn by the pawl P' carried by the lever P on each upward movement of the latter. The pawl P^2 pivoted to the frame G engages with the ratchet wheel Q' to prevent retrograde movement of the latter. The shaft Q is formed with a worm Q^2 which is in mesh with a worm gear Q^3 . The latter surrounds and is splined on the piston rod or feed bar R . The feed bar R is received in the guideway G^4 formed in the frame G and is threaded for engagement with the half nut GA which is detachably secured in place in the frame G as by the pivoted latch G^2 . With the arrangement described the rotation imparted to the feed bar R by the rotation of the gear Q^3 slowly advances the feed bar R so long as the threads of the latter are in engagement with the half nut GA . When the latter is moved out of place, however, the feed bar R may be moved parallel to its length in either direction without rotation of the gear Q^3 . A handle Q^4 secured to one end of the shaft Q forms a means for manually rotating the shaft Q to facilitate the registry of the threads of the rod R and half nut GA in securing the latter in place. With the half nut GA in place, the feed bar R may be manually advanced without oscillation of the pawl lever P , by means of the handle Q^4 . At its lower end the feed bar R carries a suitable piston R' which enters the open upper end of the ink receptacle S .

The latter, in the form shown best in Figs. 6 and 7, comprises a sheet metal cylinder closed at its lower end, except for apertures

S' , and open at its upper end. To the lower closed end of the receptacle S is secured a head portion T which is formed with a concavity or shallow groove T' curved to correspond to the curvature of the fountain roll J , which in the assembled apparatus, extends into, but does not contact with the surface of this concavity as shown in Fig. 2. In the particular construction shown in Figs. 6 and 7, the member T is cast, and is secured to the end of the cylinder S by solder plugs T^2 , which are formed with apertures T^3 registering with the apertures S' in the closed end of the ink receptacle S . This method of securing the head T to the receptacle S insures a very satisfactory and easily made connection which, while reducing the amount of soldering required, avoids all possibility of leakage along the joint between the member T and the end surface of the receptacle against which it abuts. The receptacle S rests against a suitable seat G^5 formed in the frame G and is held at the desired distance from the fountain roll J and is prevented from rotation by means of the frame part G^6 which fits against the closed end of the receptacle and also against one side of the rib T .

In the use of the apparatus described, the frame G is so connected to the part B of the printing press that the transfer roll M will contact with the ink bed E in the dotted line position of the parts shown in Fig. 2, and while moving between the dotted and full line positions of Fig. 2 except when in close proximity to its full line position in which the roll M is in engagement with the fountain roll J . By the described connections between the rock shaft H and the frame D the rocking movement of the latter causes the rock shaft H and parts connected thereto to swing back and forth between the positions shown in Figs. 1 and 2. Inasmuch as the gear segment I meshes with the spur gear J^2 attached to the fountain roll J , any rocking movement of the shaft H in either direction causes a rotary movement in the one direction or the other of the fountain roll. As the gear segment I in turning from the position shown in Fig. 2 toward the position shown in Fig. 1 approaches the last mentioned position, the projection I' of the gear segment I engages the arm K' and thus gives a partial turn to the shaft K and at the same time through the engagement of the arm K' with the stud L' of the movable frame L advances the latter from the full line position of Fig. 2 into the dotted line position of that figure. The oscillation of the shaft K through the arm K^5 , connecting rod O and the gearing actuated by the latter, imparts corresponding downward movement to the ink expelling plunger R . The extent of the movement

or feed imparted to the plunger R at each oscillation of the gear segment I may be adjusted by adjusting the distances from the axis of the shaft K at which the sleeve N is secured to the arm K⁵. As the gear segment I moves back from the position shown in Fig. 1 into the position shown in Fig. 2 the springs L² return the movable frame L and thereby the arm K', shaft K and attached parts to the position shown in Fig. 2. The gear J² and gear segment I are so proportioned that a partial turn of the latter will give several complete turns to the roll J, and inasmuch as the transfer roll M is not moved out of contact with the roll J except during a small portion of the oscillatory movement of the gear segment I, the roll J will give several turns to the roll M while the rolls J and M are in contact and thus insure a proper transfer of ink from the fountain roll J to the distributing roll M. The reversal of the direction of rotation of the rolls J and M and the freedom for endwise movement of the roll J contribute to the desired evenness with which the ink is transferred from the roll J to the roll M. In case the apparatus continues in operation after the piston R engages the lower end of the ink receptacle, the yielding connection formed by the jointed connecting rod O then yields on each feeding movement of the shaft K, and thus prevents injury to the apparatus. The film-like space provided between the fountain roll J and the wall of the groove formed in the end of the receptacle serves as a distributing space for spreading the ink discharged into this space through the orifices D².

It will be readily apparent that one ink container may be removed and another inserted quickly, and easily, and that the apparatus is readily cleaned.

Instead of having the rib T formed separately from the body of the ink receptacle, the receptacle itself may be formed from sheet metal pressed into shape as shown in Fig. 8, wherein S² represents the groove or concavity formed in the closed end of the sheet metal receptacle SA to receive the fountain roll J, and S³ represents an aperture through which ink is expelled onto the roll J.

When it is desired to avoid the cost of sheet metal ink receptacles, they may be formed of paper or paste board. In this case I preferably provide a metal head or cap, as shown in Fig. 9, wherein TA represents the metal cap and SB the paste board receptacle which is in the shape of an open ended cylinder. To prevent undesirable yielding of the paste board cylinder under the pressure to which the ink is subjected by the piston R', I prefer to provide the receptacle proper with an external support.

This may be in the form of a sheet metal sleeve U. As shown in Fig. 9, the sleeve U may advantageously be slotted at one side and proportioned to snugly hug the inclosed paste board cylinder. To permit the ready insertion and removal of the paste board cylinder the sides of the slot U² may be sprung apart by means of an inserted screw driver or like implement. In place of such a holder as is formed by the slotted sleeve U shown in Fig. 9, I may employ the holder UA shown in Fig. 10. This holder comprises a base member formed with a semi-cylindrical channel receiving the ink receptacle proper and a top member U' hinged to the base member at one side as indicated at U² and detachably secured at its opposite side, as by means of the clamping screw U³, to the base member.

It will of course be readily understood that other means than those heretofore described may be employed for giving the feeding movement to the ink expelling piston. For instance, as shown in Figs. 11 and 12, the shaft Q may be replaced by a shaft QA formed with angularly displaced crank portions Q¹⁰ on which are journaled pawls W adapted, when the shaft QA is rotated, to intermittently and successively engage and advance the feed bar carrying the ink expelling piston. The feed bar in this case is a rack bar RA. Another construction of the feeding mechanism is illustrated in Fig. 13, wherein the feeding mechanism may be identical with that employed in Figs. 1 to 4, inclusive, with the exception that the shaft Q is replaced by a shaft QB formed with crank portions for intermittently and successively advancing pawls W' and W², and the gear Q³ is replaced by a disk X splined on the threaded piston or feed rod R and formed on its face with two annularly arranged series of ratchet teeth X' and X² engaged one by the pawl W' and the other by the pawl W².

While in accordance with the provisions of the statutes I have illustrated and described the best forms of my invention now known to me, it will be apparent to those skilled in the art that changes may be made in the form of the apparatus disclosed without departing from the spirit of my invention, and that under some conditions certain features of my invention may be used without a corresponding use of other features.

Having now described my invention, what I claim as new and desire to secure by Letters Patent, is:

1. An inking appliance for a printing press comprising a readily removable container closed at one end except for one or more restricted discharge orifices and formed at its closed end with an external shallow rounded groove into which said orifices discharge, a piston movable in said container

5 tainer to thereby expel ink from the container through said orifices, a rigid rotatable roll against which the ink expelled is discharged, and means for holding said container and roll in such relative positions that the roll enters said groove but is separated from the wall of the latter by a film-like space extending circumferentially about said roll at each side of said orifices for a 10 distance of which the width of said orifices is but a small fraction.

2. An inking appliance for a printing press comprising a container closed at one end except for one or more restricted discharge orifices and provided at its closed 15 end with an external rib formed on its outer face with a shallow rounded groove into which said orifices open, a frame in which said container is mounted and formed with 20 a shoulder against which said rib engages to thereby fix the relative positions of the container and frame, and a roll journaled in said frame and extending parallel to and projecting into but not contacting with the 25 wall of said groove, and mechanism for expelling ink from said container through said orifices and for rotating the said roll.

3. An inking appliance for a printing press comprising a container closed at one 30 end except for a plurality of restricted discharge orifices and provided at its closed end with an external rib through which said orifices extend, a frame in which said container is mounted and formed with a shoulder 35 against which said rib engages to thereby fix the relative positions of the container and frame and a roll journaled in said frame in position to receive ink discharged through the different discharge orifices and 40 mechanism for expelling ink through said orifices against said roll.

4. An ink container formed of sheet metal and adapted to be inserted in an inking appliance for a printing press and to have ink 45 expelled therefrom by said appliance, said container having an end portion formed with an integral hollow rib opening internally of the container and a plurality of restricted discharge orifices formed through 50 the wall of said rib.

5. An ink container adapted to be inserted in an inking appliance for a printing press and to have ink expelled therefrom by said appliance, said container being in 55 the form of a cup pressed out of sheet metal and having its closed end portion formed with an integral hollow rib opening internally of the container and shaped to provide a shallow rounded groove in the outer 60 edge of said rib and having a plurality of restricted discharge orifices formed through the wall of said rib and opening into said groove at intervals along the length of the latter.

6. An inking appliance for a printing

press, comprising in combination a container provided with a restricted discharge orifice, means for expelling ink from said container through said orifice, a roll against which the ink so expelled is discharged, a transfer 70 roll movable from one position in which it contacts with the first mentioned roll to a second position in which it is adapted to contact with the inking bed of the press with which the appliance may be used, and 75 mechanism for moving said transfer roll back and forth between said positions, for rotating the first mentioned roll while in contact with said transfer roll, and for actuating said ink expelling means. 80

7. An inking appliance for a printing press comprising in combination a frame, a receptacle removably mounted in said frame and formed with a discharge orifice, and means for expelling ink from said receptacle comprising a plunger mounted in and axially movable in said frame and gearing mounted on said frame for slowly advancing said plunger in normal operation including parts readily separable to permit 90 a more rapid axial adjustment of said plunger in said frame on the insertion or removal of said receptacle. 85

8. An inking appliance for a printing press comprising in combination a frame, a 95 receptacle mounted in said frame and formed with a discharge orifice, and means for expelling ink from said receptacle comprising a threaded rod, means for rotating said rod in normal operation, and a threaded part normally secured in said frame in threaded engagement with said rod whereby the latter is slowly advanced as it rotates in normal operation, said part being movable out of the position in which it is 100 in threaded engagement with said rod to permit a more rapid axial adjustment of the latter. 105

9. An inking appliance for a printing press comprising in combination a frame, 110 a receptacle mounted therein and formed with a discharge orifice, and means for expelling ink from said receptacle comprising a plunger working in said frame and mechanism for advancing said plunger comprising a connecting rod formed in sections, resilient means normally holding said sections in rigid relation to one another but adapted to yield and permit the sections to move relative to one another when the resistance to the movement of the plunger exceeds a predetermined amount adapted. 115

10. An inking appliance for a printing press comprising in combination a frame, a receptacle mounted therein and formed 120 with a discharge orifice, and means for expelling ink from said receptacle comprising a plunger working in said frame and adapted to engage mechanism for advancing said plunger comprising a connecting rod com- 125

posed of two sections one of which is formed with a slot inclined to the length of said rod, a pin carried by the other section and working in said slot, one of said sections being formed with a shoulder extending transversely to the length of the rod, an arm pivoted to the other section and resilient means normally holding said arm against said shoulder whereby said sections 10 are normally held in rigid relation to one another but are adapted to move axially and angularly relative to one another when the resistance to the movement of the plunger exceeds a predetermined amount.

11. An inking appliance for a printing press, comprising in combination a container provided with a restricted discharge orifice, a piston movable in said container to expel ink therefrom through said orifice, a roll 20 against which the ink so expelled is discharged, a transfer roll movable from one position in which it contacts with the first mentioned roll to a second position in which it is adapted to contact with the inking bed 25 of the press with which the appliance may be used, and mechanism for rotating the first mentioned roll, for moving the transfer roll back and forth between said positions, and for advancing said piston in proportion to 30 the number of to and fro movements made by said transfer roll.

12. An inking appliance adapted to be attached to a printing press to supply ink to the ink bed thereof, comprising in combination, a frame adapted to be attached to a part of the printing press, a roll journaled in said frame, means for mounting an ink receptacle in said frame, a plunger mounted in said frame and adapted to engage said ink receptacle and thereby expel ink therefrom against said roll, a movable frame mounted on the said first mentioned frame, a distributing roll mounted in said movable frame and movable with the latter back and forth between one position, in which it contacts with the first mentioned roll and is out of contact with said ink bed, and a second position in which it contacts with the latter and is out of contact with the first mentioned roll, and operating mechanism adapted to be connected to and actuated by a movable part of the printing press and including means for giving said movable frame its back and forth movement and for rotating the first mentioned roll, and a pawl and ratchet mechanism for imparting a feeding movement to said plunger.

13. An inking appliance for a printing press to supply ink to the ink bed thereof, comprising a frame adapted to be attached to a part of the printing press, a roll journaled in said frame, means for mounting an ink receptacle in said frame, means for expelling ink from said receptacle against

said roll, a transfer roll connected to said frame but movable with respect thereto back and forth between one position in which it contacts with the first mentioned roll and is out of contact with said ink bed, and a second position in which it contacts with the latter and is out of contact with the first mentioned roll, and means adapted to be connected to and actuated by a movable part of the printing press for moving said transfer roll from one of said positions to the other, for rotating the first mentioned roll and for actuating said ink expelling means.

14. An inking appliance for a printing press to supply ink to the ink bed thereof, comprising a frame adapted to be attached to a part of the printing press, a roll journaled in said frame, means for mounting an ink receptacle in said frame, a transfer roll connected to said frame but movable with respect thereto back and forth between one position in which it contacts with the first mentioned roll and is out of contact with said ink bed, and a second position in which it contacts with the latter and is out of contact with the first mentioned roll, and mechanism adapted to be connected to and actuated by a movable part of the printing press and comprising means for moving said transfer roll from one of said positions to the other, and for rotating the first mentioned roll, and means for expelling ink from said receptacle against said roll, said last mentioned means including a yieldable element serving as a safety device to prevent injury to the appliance when the ink is all expelled from said container.

15. An inking appliance for a printing press to supply ink to the ink bed thereof, comprising a frame adapted to be attached to a part of the printing press, a roll journaled in said frame, means for mounting an ink receptacle in said frame, means for expelling ink from said receptacle against said roll, a transfer roll connected to said frame but movable with respect thereto back and forth between one position in which it contacts with the first mentioned roll and is out of contact with said ink bed, and a second position in which it contacts with the latter and is out of contact with the first mentioned roll, and means adapted to be connected to and actuated by a movable part of the printing press for moving said transfer roll from one of said positions to the other and for rotating the first mentioned roll while said transfer roll is in contact therewith.

16. An inking appliance for supplying ink to the ink bed of a printing press, comprising in combination a frame adapted to be attached to a part of the printing press, a roll journaled in said frame, a gear secured to said roll, means for mounting an ink receptacle in said frame, a transfer roll con-

5 nected to said frame but movable with respect thereto back and forth between one position in which it contacts with the first mentioned roll and is out of contact with said ink bed, and a second position in which it contacts with the ink bed and is out of contact with the first mentioned roll, a rocking element journaled in the first mentioned frame and adapted to be connected to and 10 rocked by a movable part of the printing press and comprising a gear segment meshing with the gear secured to the first mentioned roll, and means actuated by said rocking element for expelling ink from said 15 receptacle against the first mentioned roll, and for moving said transfer roll from one of said positions into the other position.

17. An inking appliance for supplying ink to the ink bed of a printing press, comprising in combination a frame adapted to be attached to a part of the printing press, a roll journaled in said frame, a gear secured to said roll, means for mounting an ink receptacle in said frame, a transfer roll 25 connected to said frame but movable with respect thereto back and forth between one position in which it contacts with the first mentioned roll and is out of contact with said ink bed, and a second position in which 30 it contacts with the ink bed and is out of contact with the first mentioned roll, a rocking element journaled in said frame and adapted to be connected to and rocked by a movable part of the printing press and 35 comprising a gear segment meshing with the gear secured to the first mentioned roll, means actuated by said rocking element for expelling ink from said receptacle against the first mentioned roll, and means actuated 40 by said rocking element as it approaches one limit of its oscillatory movement for moving said transfer roll from one of said positions into the other position.

18. An inking appliance for supplying ink 45 to the ink bed of a printing press, comprising in combination, a frame adapted to be attached to a part of the printing press, a roll journaled in said frame, a gear wheel secured thereto, means for mounting an ink 50 receptacle in said frame, a plunger mounted in said frame and movable to expel ink from said receptacle against said roll, gearing mounted on said frame for advancing said plunger and comprising a ratchet and 55 ratchet lever, an oscillating arm journaled on said frame, an operating connection including a yieldable element between said oscillating arm and said gearing, a transfer roll connected to said frame but movable 60 with respect thereto back and forth between one position in which it contacts with the first mentioned roll and is out of contact with said ink bed, and a second position in which it contacts with said ink bed and is 65 out of contact with the first mentioned roll,

a rocking element journaled in the first mentioned frame and adapted to be connected to and rocked by a movable part of the printing press and comprising a gear segment in mesh with said gear, and means for transmitting motion from said rocking element to said oscillating arm and to said movable frame. 70

19. An inking appliance for a printing press to supply ink to the ink bed thereof, comprising a frame, means adapted to adjustably attach said frame to a part of the printing press, a roll journaled in said frame, means for mounting an ink receptacle in said frame, a plunger mounted in said frame and adapted to engage said ink receptacle and thereby expel ink therefrom against said roll, a movable frame mounted on the said first mentioned frame, a transfer roll mounted in said movable frame and 80 movable with the latter back and forth between one position in which it contacts with the first mentioned roll and is out of contact with said ink bed, and a second position in which it contacts with the latter and is out 85 of contact with the first mentioned roll, and means adapted to be connected to and actuated by a movable part of the printing press for giving said movable frame its back and forth movement, and for rotating the first 90 mentioned roll. 95

20. An inking appliance adapted to be attached to a printing press to supply ink to the ink bed thereof, comprising in combination, a frame adapted to be attached to a part of the printing press, a roll journaled in said frame, means for mounting an ink receptacle in said frame, a plunger mounted in said frame and adapted to engage said ink receptacle and thereby expel ink therefrom against said roll, a movable frame mounted on the said first mentioned frame, a transfer roll mounted in said movable frame and movable with the latter back and forth between one position in which it contacts with the first mentioned roll and is out of contact with said ink bed, and a second position in which it contacts with the latter and is out of contact with the first mentioned roll, means adapted to be connected to and actuated by a movable part of the printing press for giving said movable frame its back and forth movement, and for rotating the first mentioned roll and for 100 advancing said plunger. 105

21. The combination in means for supplying ink to printing presses, of an ink distributor; a tube containing ink and having an opening through which the ink escapes; a plunger in the tube; a feed screw bearing against the plunger; a half nut, capable of being raised, having a thread engaging the threads of the feed screw; and ratchet mechanism by which the feed screw is turned, the feed screw being relieved when the half 110 115 120 125 130

nut is raised so as to allow the feed screw to be quickly withdrawn after the ink has been discharged from the tube.

22. In a printing press, in combination with the inking rollers, of a removable ink receptacle, means embracing the receptacle for detachably clamping the receptacle in position to supply ink to the inking rollers, a plunger entering into the receptacle to

force the ink therefrom to feed the inking rollers, means for advancing the plunger comprising a screw and nut, and means for releasing the nut to permit the quick return of the plunger.

JOHN McCLURE.
